MARTIN HILL ITTNER, OF JERSEY CITY, NEW JERSEY.

HYDROGENATING OILY MATERIAL CONTAINING UNSATURATED BODIES.

1,271,575.

Specification of Letters Patent. Patented July 9, 1918.

Application filed May 6, 1914. Serial No. 836,624.

To all whom it may concern:

Be it known that I, MARTIN HILL ITTNER, a citizen of the United States, residing at No. 202 Ege avenue, Jersey City, Hudson county, State of New Jersey, have invented 5 certain new and useful Improvements in Hydrogenizing Oily Material Containing Unsaturated Bodies; and I do hereby declare the following to be a full, clear, and 10 exact description of the invention, such as will enable others skilled in the art to which it appertains to make and use the same.

My invention relates to certain new and useful improvements in hydrogenizing oily 15 material containing unsaturated bodies, *i. e.*, hydrogenizing fatty acids or their esters either wholly or partially, as the case may be, and by the aid of a catalyst whose presence, under suitable thermal conditions, initiates and maintains the hydrogenization. 20

The main characteristic feature of my invention consists in forcing the oily material, mixed with the catalyst and under appropriate thermal conditions through an orifice 25 or opening, so related to the hydrogen employed in the operation, that the gas will be intimately mixed with the oily material and the catalyst, the constituent elements of the mixture being brought into such close 30 contact relation with each other as to insure a rapid and effective progress of the hydrogenizing operation. Specific modifications of the generic invention will also be herein-after particularly described.

35 In the accompanying drawing,—I have illustrated, in vertical central section and partial elevation, suitable apparatus appropriate to the practice of the invention.

Referring to the drawing,—F indicates a 40 suitable metal tank or receptacle for the reception of the unsaturated oily material to be hydrogenized, which material may be admitted through the supply pipe C provided with a shut-off cock x. The receptacle F is preferably provided with a conical bottom having a heating jacket J adapted 45 to be supplied with steam or other suitable heating agent for the purpose of maintaining the appropriate temperature in the receptacle F.

At its lower end, the receptacle F terminates in an outlet pipe a suitably covered with heat-insulating material, which may either discharge through a branch a' or into 50 a pump chamber P, actuated from the steam

cylinder P', a suitable three-way valve a², being provided, as shown, to direct the flow of the material. The pump chamber P discharges through the outlet pipe b, which, in turn, communicates with the pipes c, d, 60 each having a hand-valve, c', d' so that, by appropriate manipulation of the said valves, the pipe b will discharge through the pipe c or the pipe d, as desired. The pipe c enters a heater H of any appropriate kind 65 adapted to heat the entering pipe externally before it issues from the heater in the form of the return pipe K, which latter communicates with a pipe B extending into the receptacle F. A thermometer T enters 70 the pipe B, at its upper end, so as to register the temperature of the ingoing mixture. At its lower end, the pipe B is provided with an aspirator B' consisting of an inner sleeve flaring outwardly at its ends and having a 75 central aperture or apertures, as indicated at e establishing communication between the interior of the sleeve with the annular space between the sleeve and the pipe B. Into this annular space enters the pipe f having 80 a hand-valve f', and having a branch g which may be opened or closed at will by the hand-valve g' so as to put the pipe f into full communication with the interior of the receptacle F above the level of the 85 oil therein or to shut off such communication wholly or partially as desired. The pipe f leads from the source which supplies hydrogen to the apparatus. A pipe C' having a hand-valve M leads from the top of 90 the apparatus to withdraw any gas that may become vitiated, and which may require purification before re-use. A pipe G communicates with and forms a continuation of the aspirator and extends downward 95 to near the lower end of the receptacle F and below the surface of the oily material undergoing hydrogenation.

In the practice of the invention, the mixture of the oily material containing unsaturated bodies, (for instance fatty acids or their esters) with the catalyst employed, is admitted into the chamber F through the pipe C, and rises to a suitable level in the receptacle, leaving a space in the upper part 100 thereof. The air in this upper space is then replaced by hydrogen gas admitted through the pipe f and the branch g thereof.

The valve a² being in the open position shown in the drawing, the pump P is started 110

and the fatty acids or their esters, mixed with the catalyzer, are pumped through the pipe K and enter the apparatus through the pipe B, passing the thermometer T, which indicates the temperature of the mixture. The mixture, under pressure, passes through the aspirator B' whereupon hydrogen gas is drawn in through the aperture e and is intimately mixed with the mixture of fatty acids or their esters and the catalyzer.

The mixture of fatty acids or their esters, catalyzer and hydrogen gas passes through the tube G into the chamber F. It may be made to discharge, as shown, below the surface of the fatty acids or their esters within the chamber F, whereby the hydrogen gas not absorbed bubbles up through the fatty acids or their esters and keeps them in a state of motion, thereby preventing the catalyzer from settling out of the mixture and further adding to the absorption of hydrogen by the fatty acids or their esters.

Hydrogen gas may be introduced from without through the pipe f by manipulating the cock f', or it may be drawn in from the upper part of the chamber through the cock g' controlled, as shown, from without the chamber. The gas in the upper part of the chamber F may be withdrawn through the pipe C', if said gas becomes vitiated, and, after purification, may be returned to the apparatus. The fatty acids or their esters may be heated to a suitable temperature, by means of steam admitted through the pipe z' and taking its exit through the pipe z, or by means of the heater H which may likewise be heated by steam as indicated. I find the most suitable temperatures for operating on the different fatty acids or their esters, when nickel is used as the catalyzer to lie between 130° C. and 200° C., although the process will work outside of either limit.

I do not confine myself to the exact type of apparatus herein described, as I find that the process can be worked to advantage with a plurality of places where a jet of fatty acids or their esters mixed with the catalyzer may be forced into intimate contact with hydrogen gas, and I further find that it may be advantageous to employ several chambers similar to F in series.

The fatty acids or their esters, mixed with catalyzer, after issuing from the tube G may be passed a second time through the tube K for further treatment in the same apparatus, or the mixture may be forced through the pipe d and cock d' into another similar apparatus.

The mixture of fatty acids or their esters with catalyzer, may, at any time, be withdrawn and the catalyzer removed by well known methods, so as to be again employed in hydrogenizing fatty acids or their esters, and the hydrogenized fatty acids and their esters may thus be left in condition for use.

The process will operate without maintaining great pressure within the chamber F, although I prefer to maintain a slight pressure within F, over the atmospheric pressure, to prevent the possibility of air leaking in and forming an explosive mixture with the hydrogen gas. The process may, however, be worked to advantage with a considerable pressure within the chamber F, or will even continue to work under a partial vacuum within F due to insufficient hydrogen gas being introduced through f to compensate for the absorption.

Having thus described my invention, what I claim is:

1. The process of hydrogenizing oily material containing unsaturated bodies, which comprises forcing the material, mixed with a catalyzer, through an orifice or opening, which orifice or opening communicates with a supply of hydrogen gas, and causing the mixture of oily material and catalyzer to entrain or draw in hydrogen and thereby effecting an intimate mixture of the oily material and the hydrogen gas; substantially as described.

2. The process of hydrogenizing oily material containing unsaturated bodies, which comprises forcing the material, mixed with a catalyzer, through an orifice or opening, which orifice or opening communicates with a supply of hydrogen gas, whereby hydrogen gas is drawn into the mixture of oily material and catalyzer and whereby an intimate mixture of the oily material and the hydrogen gas is brought about, and discharging said mixture into an inclosed space containing an atmosphere of hydrogen gas; substantially as described.

3. The process of hydrogenizing oily material containing unsaturated bodies, which comprises forcing the material, mixed with a catalyzer, through an orifice or opening, which orifice or opening communicates with a supply of hydrogen gas, whereby hydrogen gas is drawn into the mixture of oily material and catalyzer and whereby an intimate mixture of the oily material and the hydrogen gas is brought about, and discharging said mixture into an inclosed space containing an atmosphere of hydrogen gas, and also containing a body of the oily material mixed with the catalyzer; substantially as described.

4. The process of hydrogenizing oily material containing unsaturated bodies, which comprises forcing the material, mixed with a catalyzer, through an orifice or opening, which orifice or opening communicates with a supply of hydrogen gas, whereby hydrogen gas is drawn into the mixture of oily material and catalyzer and whereby an intimate mixture of oily material and the hydrogen gas is brought about, and discharging said mixture into an inclosed

space containing a body of the oily material mixed with the catalyster and containing an atmosphere of hydrogen gas, withdrawing the oily material together with the catalyster contained therein, and again forcing them into the same chamber and causing them again to draw in hydrogen gas and to be brought into intimate contact therewith; substantially as described.

5 5. The process of hydrogenizing oily material containing unsaturated bodies, which comprises forcing the material, mixed with a catalyster, through an orifice or opening, which orifice or opening communicates with a supply of hydrogen gas, whereby hydrogen gas is drawn into the mixture of oily material and catalyster and whereby an intimate mixture of the oily material and the hydrogen gas is brought about, and discharging said mixture into an inclosed space containing a body of the oily material mixed with the catalyster and containing an atmosphere of hydrogen gas, withdrawing the oily material together with the catalyster contained therein, and again forcing them into the same chamber and causing them again to draw in hydrogen gas and to be brought into intimate contact therewith, said hydrogen gas being supplied from the atmosphere of the chamber itself; substantially as described.

10 6. The method of hydrogenizing oily material containing unsaturated bodies, which comprises forcing said material, mixed with a catalyster, together with hydrogen gas, simultaneously under pressure through the same opening, whereby the oily material, the catalyster, and the hydrogen gas are

15

20

25

35

brought into intimate contact; substantially as described.

7. The process of treating oily material and the like containing unsaturated bodies which comprises confining a body of said material, admixed with a catalyster, in juxtaposition to a hydrogen-containing gaseous medium, in withdrawing from said body portions thereof, in passing such portions through some portion of said gaseous medium; whereby entrainment of some portion of the latter occurs, and in causing the withdrawn oil and entrained gas to enter said body of oil beneath the surface thereof; whereby saturation of at least a portion of said unsaturated bodies is effected.

8. The process of treating oily material and the like containing unsaturated bodies which comprises confining a body of said material, admixed with a catalyster, in juxtaposition to a hydrogen-containing gaseous medium under pressure, in continuously withdrawing from said body portions thereof, in passing said portions through some portion of said gaseous medium; whereby entrainment of some portion of the latter occurs, and in causing the withdrawn oil and entrained gas to enter said body of oil at a point well beneath the surface thereof; whereby saturation of at least a portion of said unsaturated bodies is effected.

In testimony whereof I affix my signature, in presence of two witnesses.
